FABRIC AND GARMENT CONSTRUCTION

Charles D. Williamson, Fort Worth, Tex.

Application August 25, 1944, Serial No. 551,162

2 Claims. (Cl. 139—383)

This invention relates to textile and clothing manufacture and improvements in garment construction whereby all types of bifurcated garments, such as pants, or the like, can be properly reinforced at points which are most subject to wear and its primary object resides in the provision of a specially designed and woven fabric wherein certain definite areas of the cloth, such as a strip of any desired width, is integrated into the bolt when woven, which may be stronger than the body of the cloth and thus substantially reinforced at this point.

An object of the invention, therefore, is to provide a fabric capable of peculiar adaptation to the manufacture of work clothing, particularly in strengthening portions of garments such as pants, where wear and undue stresses occur as at the knees and thighs and afford an economical and durable garment without increase in the cost of manufacture of the garment and only a negligible increase in the production of the fabric.

Another object of the invention is that of providing a fabric in which a portion of the longitudinal warp yarns woven into the cloth are increased in number or stronger than those of the main body thereof as, for example, a strip of predetermined width and running parallel to and spaced a predetermined distance from one of the selvedges of the fabric whereby certain portions of garments, as pants, may be cut from the fabric in the usual manner yet providing for the location of the reinforced portion in the approximate center of the pants leg in front of the wearer and extending the full length thereof thus presenting strengthened portions of the cloth to wear at the points where such wear is usually most prevalent.

Broadly, the invention seeks to comprehend the provision of a fabric manufacture and garment construction calculated to increase wear of work clothing without resorting to conventional means of reinforcing points of wear by adding thicknesses of cloth to such garments which methods often result in bulkiness of portions of the garment and much discomfort to the wearer.

While the foregoing objects are paramount, other and lesser objects will become manifest as the description proceeds taken in connection with the appended drawing wherein:

Figure 1 illustrates a fragmentary length of fabric having a strip woven thereinto in accordance with the invention which is stronger than the body thereof and showing, in dotted lines, the manner in which the front and back portions of trousers can be cut therefrom.

Figure 2 is a front view of a pair of trousers

made in accordance with the invention and illustrating the strengthened strip in the fabric extending the full length of the front of each leg.

Figure 3 further illustrates the strengthened strips in the fabric running the full length of each trouser leg.

Figure 4 is a cross-sectional view of the invention illustrating the relationship of the longitudinal warp yarns comprising the strengthened strip integrated into the fabric, and

Figure 5 fragmentarily illustrates the strengthened strip in comparison to the main body of the cloth and its relation to the selvedge.

In a recent authoritative survey conducted by 15 persons interested in textile manufacture it was determined that the greatest wear on work pants is at the knee while the thigh received the next greatest wear. In order to remedy this situation various conventional methods have been employed, such as substituting heavier cloth for the entire garment, thereby greatly increasing the cost, or reinforcing at primary points of wear with additional thicknesses of cloth which results in both increase in cost and ill formed and 20 ill fitting, uncomfortable garments.

The invention, therefore, comprises weaving fabric so as to integrate thereinto a longitudinal strip or section 1 by increasing the number of longitudinal warp yarns per inch, or using a 25 stronger yarn, while employing the standard number of yarns in the transverse weave and in the main body 2 of the cloth and locating the stronger strip, which may be any desired width, depending on its ultimate use, a desired distance from one of the selvedges 3, in a manner illustrated in Figures 1, 4 and 5.

This arrangement may also be accomplished by inserting into the strip 1 a number of heavier or larger warp yarns running lengthwise of the 30 body 2 of the cloth, although it is not necessarily desirable to thicken the fabric at this point, or employ two ply twisted, combed or fiber yarns of greater strength. Obviously, many methods may be employed in providing the strip 1, any of which 35 may be accomplished without difficulty and without requiring any especially designed equipment.

One of the primary purposes of the invention being to afford a stronger and more durable garment, Figure 1 illustrates, in dotted lines, the manner in which the back and front sections 4 and 5 of the garment are laid out and cut from the finished fabric, in the usual manner with a minimum of waste. It will be noted that the front section 5 is always cut from the edge 3 of the cloth so that the strengthened strip, which

is properly spaced from the selvedge 3, will extend longitudinally of the front section 5 and spaced from its sides so that, when the trousers 6 are completed, the reenforced portion 1 will extend down the front of the trouser legs 7, in the manner illustrated in Figures 2 and 3.

The terms "pants," "trousers" and "garment" herein employed are intended to embrace any and all types of bifurcated garments, as well as shirts, and the like, and including overalls and unionalls.

By causing the reenforced or strengthened strip 1 to run full length of the legs 6 all of the usual points of wear are protected as at the knee 8 or the thigh 9, as depicted in Figure 3. While providing for the strengthening of the critical points of wear it is obviously economical to provide a fabric having a definitely located reenforced or strengthened portion such as the strip 1.

In the manufacture of trousers it is considered practical to weave the fabric in widths of about 30 inches to minimize waste and to locate the stronger strip 1 approximately 2½ inches from the selvedge 3. The strip 1 should be approximately five inches wide in order to afford a desirable wearing surface. When the strip 1 is of the width above mentioned and located the stated distance from the selvedge 3 the front section 5 of the garment leg 7 can be cut so that the strip 1 will be centrally located therein, as shown in Figure 2. In this manner no greater waste will result in cutting than by the conventional methods.

Obviously certain changes and modifications in the manner of weaving the fabric to provide the strengthened portion 1 thereof may be resorted to from time to time by persons skilled in the art and such changes and modifications so resorted to as may be considered as falling within the scope of the appended claims.

What is claimed is:

1. An improved article of manufacture, a woven sheet for fabricating trousers, said sheet having

a selvedge, a continuous area of increased wear quality extending parallel to said selvedge comprising a group of yarns having, as a group, comparatively high wearing properties, a relatively narrow area formed of yarns of comparatively low wearing properties between said area of increased wear quality and selvedge, a second, comparatively wide area formed of yarns of relatively low wearing properties at the opposite side of said area of increased wear quality, the relative widths of said areas being such that sections cut lengthwise of said area of increased wear quality with equal widths of material of lesser wear quality at opposite sides thereof will form trouser front panels having said area of increased wear quality extending lengthwise and centrally thereof, and sections cut lengthwise from the remaining portion of said second, wider area of lesser wear quality will form trouser back panels.

2. An improved article of manufacture, a woven sheet for fabricating trousers, said sheet having a selvedge at one side, a narrow area of lesser wear quality extending along said selvedge and composed of yarns of relatively low wearing properties, a wide area of lesser wear quality extending along the opposite edge of said sheet and composed of yarns of relatively low wearing properties, and an area of increased wear quality containing a group of yarns having, as a group, relatively high wearing properties between said first two areas, the width of said area of increased wear quality and said narrow area of lesser wear quality being such that sections cut lengthwise therefrom and of a width extending transversely of the sheet from the selvedge into the wide area of lesser wear quality a distance equal to the width of said narrow area will form trouser front panels each having an area of increased wear quality extending lengthwise and centrally thereof.

CHARLES D. WILLIAMSON.
